[57] CLAIM

The ornamental design for a hinge mounting for a high voltage fuse, substantially as shown and described.

DESCRIPTION

FIG. 1 is a perspective view of a preferred embodiment of a hinge mounting for a high voltage fuse according to the invention;

FIG. 2 is a front elevational view of the hinge mounting of FIG. 1;

FIG. 3 is a side elevational view of the hinge mounting of FIG. 1;

FIG. 4 is a top view of the hinge mounting of FIG. 1; FIG. 5 is a bottom view of the hinge mounting of FIG. 1; and

FIG. 6 is a perspective view of an alternative embodiment of the mounting according to the invention.

A bracket and a contact are shown in broken lines in the Figures for illustrative purposes only.
